UNITED STATES PATENT OFFICE.

JULIUS MAGGI, OF KEMPTHAL, SWITZERLAND, ASSIGNOR TO JULIUS MAGGI & CO., OF SAME PLACE.

COMPRESSED-FOOD PACKAGE.

SPECIFICATION forming part of Letters Patent No. 395,243, dated December 25, 1888.

Application filed June 23, 1888. Serial No. 277,984. (No specimens.)

To all whom it may concern:

Be it known that I, JULIUS MAGGI, a citizen of the Republic of Switzerland, residing at Kemptthal, in the Republic of Switzerland, 5 have invented certain new and useful Improvements in a Compressed-Food Packages, of which the following is a specification.

This invention relates to compressed-food packages, and has for its object to provide 10 such a package that will not be affected by the moisture and will be easily broken at any desired point; and it consists in the improved combination of parts, as will be hereinafter more particularly described, and pointed out 15 in the claim.

Referring to the accompanying drawings, Figure 1 is a longitudinal sectional view of a package, and Fig. 2 is a side view of the same.

A represents the contents of the package, 20 which may consist of any desired article, but which in this instance consists of compressed tablets a' , a^2 , a^3 , a^4 , a^5 , and a^6 , preferably of a round or circular form. These tablets may be composed of any desired material—such as ingredients for soup, &c.— 25 which in this instance are of such a size that one tablet will make enough soup for six persons. After the tablets have been compressed separately the desired number are placed 30 together, one upon the other, as shown in Fig. 1, and are then covered with a wrapper of tin-foil, or other moist-proof material, either with or without being compressed together. In this condition all that is necessary 35 when it is desired to use any of the tablets is to break off as many as required without taking off the wrapper, the tin-foil tearing so easily as to practically offer no resistance; but as the tin-foil is so easily torn it 40 would be liable to become so torn or damaged in shipping and handling as to render it useless as a moist-proof covering, and thus fail to preserve the contents. To overcome this

defect it is necessary to provide an additional wrapper of a more substantial material—as, 45 for instance, parchmentized paper, C—which is put around the tin-foil and secured at the end by folding or sealing. As this material is so strong as to prevent injury to the tin-foil, it is consequently so strong as to prevent 50 the package being broken at any desired point, as could be done with the wrapper of tin-foil. I have found, however, that by perforating this outside wrapper with rows of small apertures i' , i^2 , i^3 , i^4 , and i^5 , and so placing 55 the wrapper that these apertures will register with the divisions between the tablets, the package can be broken almost as easily as it could be without the additional wrapper. In this manner a most useful article 60 is produced for family use or for travelers, as the package can be taken into all climates without deterioration or loss, and can be opened without the necessity of un- 65 wrapping the entire package, as all that is necessary is to break the package at a row of apertures as will take off as many tablets as are required for that time.

Having thus described my invention, I claim and desire to secure by Letters Patent of the 70 United States—

In a compressed-food package, the combination of a series of tablets, one upon the other, a fragile moist-proof wrapper, and an additional strong protecting-wrapper provided with rows of apertures registering with the divisions between the tablets, substantially as described.

In testimony whereof I have signed this specification in the presence of two subscribing 80 witnesses.

JULIUS MAGGI.
